FILTERING ELEMENT

Andrew Boiano, Rochester, N. Y.

Application January 12, 1937, Serial No. 120,259

3 Claims. (Cl. 210—170)

My present invention relates to filters and more particularly to small filtering units adapted to be used in conjunction with containers and packages of liquids to prevent impurities from issuing when the contents are emptied or drawn off, and it has for its object to provide a simple, inexpensive and efficient unit of this kind. The improvements relate in part to a provision for the adaptation of the unit to the container and to the provision of renewable filtering media that can be discarded when fouled and readily replaced at small expense. To these and other ends, the invention resides in certain improvements and combinations of parts, all as will be hereinafter more fully described, the novel features being pointed out in the claims at the end of this specification.

In the drawing:

Fig. 1 is a central vertical sectional view broken away at top and bottom of a dispensing container fitted with a filtering unit constructed in accordance with and illustrating one embodiment of my invention;

With respect to its position in Fig. 1, Fig. 2 is a bottom end view of the unit;

Fig. 3 is a corresponding top end view of the unit;

Fig. 4 is a side elevation of the unit, and

Fig. 5 is a plan view of a filtering disk applied at the end of the unit.

Similar reference numerals throughout the several views indicate the same parts.

Although it will be obvious from the ensuing description and explanation that my unit and features thereof are applicable to filtering in various environments, I have in the illustration thereof elected to show it in connection with a kerosene reservoir for oil burning heaters. Referring more particularly to the drawing, I indicate a basin mounted on a standard 2 placed conveniently to the burner, which is fed therefrom through a pipe 3 that drains the basin. A can or drum 4 containing the oil, in which package it may be purchased by the user, has a threaded neck 5 provided with a screw cap closure

6. Projecting through the center of the cap is a stem 7 provided with a valve head 8 on its inner end and a thrust head 9 on its outer end between which and the cap is interposed a spring 10. The under side of the valve head 8, which is the seating side, is suitably surfaced to coact with a washer 11 on the inside of the cap. It will be obvious that the spring 10 will normally hold the valve closed and hence maintain the container sealed. When, however, it is desired to put the

latter in use, it is inverted and inserted in the basin so that its shoulders rest upon conforming shoulders 12 on the latter. The thrust head 9 thereby engages the bottom of the basin and unseats the valve, as shown in Fig. 1, whereafter the contents of the container replenish the basin in a familiar manner. The flow is through the enlarged aperture 13 through which the valve stem passes.

In the practice of my invention, I provide a filtering unit that is insertable in and removable from the neck of the container without in any way interfering with the above arrangements or disturbing their functions, and in the description thereof I will for convenience use "top" and "bottom" as those terms apply in the illustrations. I provide a cylindrical hollow body element 14 having foraminous side walls, open at one end, and closed at the other end by a foraminous top end wall 15. This is soldered or otherwise secured at its top end within a rigidly relatively thick encircling band 16. It is similarly provided at its lower end with a like band 17 so that the general effect is that of a tube with an intermediate portion of its side walls perforated and its upper end interiorly closed by a perforated disk.

This intermediate portion is covered in close contact with a layer of fibrous filtering material, such as a finely woven textile in the form of a band 18, which may be wrapped thereabouts but may better be a ring that can be expanded and slipped into place over one end of the unit. At any rate, it is thinner than the bands 16 and 17 so that it lies in a depression between them and is protected thereby from lateral contacts when the unit is slipped into another tubular unit. Obviously, this band can be removed in the same way when fouled and replaced with a fresh one.

The end wall 15 is similarly covered with a disk 19 also of fibrous material and also renewable, the same being shown in detail in Fig. 5. It may be held in place by being clamped between the wall and another outer foraminous disk 20 by means of a central bolt 21.

The lower band 17 is provided at its lower end with a lateral flange 22. The unit is inserted in the neck 5 of the container, as shown in Fig. 1, preferably in spaced relation to its side walls and through the medium of a gasket 23, the flange 22 thereof rests against the mouth of the neck. Thereupon, the cap 11 is applied, pressing the flange to its seat and holding the unit firmly in place within the body of oil.

In operation, all the oil that reaches the outlet

- 13 to the interior of the basin must pass through either the lateral filter or the end filter and in passing through both until the level gets very low sufficient flow of filtered oil is maintained.
- 5 Under the circumstances chosen in this embodiment, for instance, an expensive filtering medium would not be practicable and yet oil as supplied for burners almost inevitably contains solid impurities such as scale from the interior of the
- 10 package and the burner jets are so fine that these, if permitted to reach them, cause a great deal of trouble. With my simple device, such trouble is eliminated while the cost of the filter and its renewable parts is negligible in proportion.

I claim as my invention:

1. A filtering element embodying, in combination, a hollow cylindrical and foraminous body having one closed foraminous end, rigid spaced bands surrounding the respective ends thereof, a band of fibrous filtering material covering the exposed intermediate portion of the body between the bands, and a renewable disk of fibrous material covering the closed end thereof.

2. A tubular filtering element embodying, in combination, an outwardly flanged outer end adapted to seat against the mouth of a container, a foraminous bottom end wall, an intermediate portion only of the lateral wall being also foraminous, a renewable band of fibrous material exteriorly covering the last mentioned foraminous portion and a renewable disk of fibrous material exteriorly covering the foraminous bottom.

3. The combination with a dispensing container having a neck and a mouth, of a detachable tubular filtering element extending into the neck in spaced relationship thereto embodying an outwardly flanged outer end resting against the mouth, a foraminous bottom end wall, an intermediate portion only of the lateral wall being also foraminous, a renewable band of fibrous textile material exteriorly covering the last mentioned foraminous portion, a renewable disk of fibrous material exteriorly covering the foraminous bottom, and a detachable cap on the neck sealing the flange of the filtering element against the mouth.

ANDREW BOIANO.
